UNITED STATES PATENT OFFICE.

HARRISON STREETER COE, OF LAWRENCE, KANSAS.

CLASSIFIER.

Application filed November 12, 1923. Serial No. 674,105.

The present invention relates to wet classifiers and has for its object the provision of an improved wet classifier. Certain features herein described and claimed were disclosed in my prior application Serial No. 434,576, filed January 3, 1921, copending with and abandoned in favor of this application.

The improved wet classifier of the invention belongs to that general type in which advantage is taken of the differential rate of settling of fine or light solid particles and coarse or heavy solid particles in a liquid (such as water) for the purpose of effecting a separation of the fine and coarse particles into two classes or products. In apparatus of this type the solid particles in the form of a pulp, that is, mixed with an appropriate liquid, are subjected to settling by gravity in the course of which the coarse or heavy particles settle more rapidly than do the fine or light particles. In consequence of this differential rate of settling between the coarse or heavy particles and the fine or light particles, the fine or light particles remain in large part suspended in the supernatant liquor, while the coarse or heavy particles in large part settle towards and on the bottom of the apparatus. Wet classifiers of this type are used extensively in ore dressing operations as well as in many metallurgical and chemical operations. In the dressing and metallurgical treatment of ores, the ore is first crushed and ground to relatively small particles, usually in the presence of an appropriate liquid such, for example, as water. The resulting mixture of finely ground ore particles and liquid constitutes the ore pulp and is fed to the classifier wherein is effected the desired separation of the coarse or heavy particles from the fine or light particles. The coarse or heavy particles are frequently described as the "sands", while the light or fine particles are frequently called "slimes".

The improved apparatus of the invention comprises a vessel having an inclined bottom surface of which a substantial area is above the normal operating liquid level in the vessel and constitutes a draining area. A solids discharge outlet is associated with this draining area and a conveying element is operatively mounted in proximity to the bottom surface of the vessel and is provided with a plurality of scoop-like members adapted to move through the liq-

uid in the vessel and gather up and remove therefrom a quantity of the solid material settling towards the bottom of the vessel and to carry such solid material along an annular path across the draining area to the solids discharge, while at the same time permitting the drainage of liquid from the solid material as it is carried along the path. In the course of the movement of the conveying element, the scoop-like members pass below the normal liquid level in the vessel and engage material collecting at the outer part of the bottom and below the liquid surface and drag such material over the bottom surface out of the liquid zone and over the draining area or drainage zone above the liquid level. The conveying element ordinarily carries scrapers or plows working in conjunction with the scoop-like members and adapted to prevent such solid material as may escape from the scoop-like members from lodging on the inner area of the draining zone or area whereby the inner area of the draining zone is kept clear and unobstructed for the free passage of the draining liquid back to the body of the pulp in the vessel.

The construction and mode of operation of what I now regard as the preferred embodiment of the improved wet classifier of the invention will be understood from the following description taken in connection with the accompanying drawings, in which:

Fig. 1 is a plan of the apparatus; Fig. 2 is an elevation of the apparatus, and Fig. 3 is a sectional elevation taken on the section line 3-3 of Fig. 2.

In the apparatus illustrated in the accompanying drawings, the settling vessel or basin 5 is square in section. I prefer to construct the settling vessel or basin of square section in classifiers up to about 20 feet in width, while in larger apparatus I prefer to construct the settling vessel or basin of circular section.

The settling basin has an inclined bottom 6, preferably pitched at an angle of about 20° with the horizontal. The upper edge or rim of the settling vessel is substantially in a horizontal plane so that the vessel has a relatively deep lower end and a relatively shallow upper end.

A feed box 7 is associated with one side of the relatively deep lower end of the settling vessel. The pulp to be treated in the classifier flows into the feed-box 7 from a

feed-pipe 8 and over an adjustable weir 9 into the settling basin. The overflow of the classifier is taken off at the opposite corner of the deep lower end of the settling vessel. 5 To this end an L-shaped overflow discharge box 10 is associated with the opposite corner of the settling vessel. The "slimes" flow from the settling basin over the adjustable weirs 11 into the box 10 and thence to the 10 "slimes" discharge outlet 12.

The conveying element of the classifier is carried by an inclined shaft 13. This shaft is operatively carried by a super-structure comprising an overhead beam 14 and two 15 uprights 15. The shaft 13 is centrally disposed with respect to the inclined bottom 6 of the settling vessel and is mounted perpendicular to the plane of the inclined bottom 6. The shaft 13 is suspended in appropriate 20 bearings carried by the super-structure and is adapted to be driven by a gear wheel 16 and cooperating worm 17; the worm being driven by a pulley 18 and co-operating belt 19 from any suitable power 25 source.

A circular spider 20 is secured to the shaft 13 at its lower end and in proximity to the inclined bottom 6. The external periphery 30 of the spider 20 is several inches in width or depth, but its bottom 21' is a substantial distance above the bottom 6 of the settling vessel to allow the solids (sands) to pass freely thereunder. A circular ring 22, somewhat wider or deeper than the peripheral 35 rim 21, is arranged concentric with and spaced from the rim 21.

A plurality of spaced scoops 23 are arranged between the rim 21 and the ring 22 and are bolted to the rim and ring to form a 40 substantially unitary structure. The scoops 23 are of substantially the same height or depth as the ring 22. The scoops 23 are so arranged that their concave surfaces are in front during the normal operating rotation 45 of the conveying element, indicated by the arrow in Fig. 1, so as to gather up and carry the solids (sands) in a manner to be later described. It should be understood that the scoops 23 may be mounted about the shaft 13 50 in any appropriate manner. The presence of the rim 21 and ring 22 is not essential to the operation of the scoops, but this construction together with the spider 20 gives unusual strength and rigidity. It is sometimes 55 advantageous to modify the shape of the scoops 23. They may, for example, be made V-shaped instead of in the shape indicated in Fig. 1.

Each of the four spokes of the spider 20 60 carries a rake or scraper 24. The rakes 24 are mounted at progressively varying distances from the shaft 13 with the object of working over substantially the entire area of the inclined bottom 6 directly beneath the 65 spider 20. The lower edges of the rakes

move in proximity to the inclined bottom 6. The rakes subserve different purposes below and above the liquid level respectively. Below the liquid level they operate to agitate the accumulated solid material so as to permit 70 it to flow into the path of the scoops. Above the liquid level they may operate to work the solid material escaping or slopping over from the sides of the scoops in three different ways depending upon the angle at which 75 they are set. Accordingly the rakes may be set so as to work the solid material on the draining area away from the center of the draining area, or to push the solid material ahead of them over the surface of this area, 80 as illustrated in the drawings, or to work the solids inwardly toward the center of the apparatus. Furthermore, these rakes may act merely to stir up the solid material on the draining area, this continuous stirring 85 serving to keep the solids in such condition that they are readily washed back into the pulp by even a relatively small amount of liquid.

The normal operating liquid level in the 90 settling basin 6 will, of course, be determined by the height of the adjustable weirs 9 and 11. In Figs. 2 and 3 of the accompanying drawings, dotted lines A indicate approximately the normal operating liquid 95 level in the settling basin. A solids (sands) discharge outlet 25 is provided on the draining area section of the inclined bottom 6. The discharge outlet 25 is positioned in the path of the scoops 23 and just preceding or 100 in advance of the point where these scoops return into the liquid in the settling vessel, after having passed over the draining area of the inclined bottom 6.

The operation of the apparatus is as follows. The pulp to be subjected to the classifying treatment flows into the feed box 7 and over the weir 9 into the settling vessel or basin 5. The level of the pulp in the settling basin is approximately indicated 110 by the dotted lines A of Figs. 2 and 3. The solid particles in the pulp undergo differential settling in the basin 5, the fine or light particles remaining in large part in suspension in the liquid while the coarse or 115 heavy particles settle towards and on the bottom of the vessel. The fine or light particles in suspension are carried away with the overflow from the settling vessel into the box 10 and out the "slimes" discharge 120 outlet 12. The conveying element is rotated at a speed of approximately three revolutions per minute, in the case of a classifier of relatively small size. The scoops 23 move through the pulp in the settling vessel and in the course of this movement pick up and carry out of the pulp a load of the solids (sands). From the time the scoops emerge 125 from the pulp, the load of solids is carried by them without substantial loss and is per-

130

mitted to drain until the scoops reach the discharge outlet 25, where the solids are dropped through this discharge outlet into a suitable collecting receptacle.

5 It will be observed that the inclined bottom 6 of the settling basin is divided into two operative portions or sections, as already indicated, namely, a lower section containing the pulp and in which differential settling takes place as hereinbefore described, and an upper or draining section in which the solids removed from the pulp by the rotating scoops are permitted to drain. The rakes 24 in passing over the 10 upper or draining area of the inclined bottom 6 keep this area substantially free of solid matter escaping from the sides of the scoops and thereby permit the free and ready flow of the liquor draining from the 15 scoops 23 across the draining area back into the pulp.

Below the liquid level the rakes 24 have two functions. First, to gently stir the settled sands so that any entrained slimes may 20 escape, and second, to convey the settled solids into the path of the annular system of conveying scoops or buckets, which ordinarily is accomplished by agitating or stirring the settled solids sufficiently to permit them 25 to flow into this path. But while the rakes may be set so as to work the settled solids toward the periphery of the lower or settling section of the vessel, they may, under certain circumstances, also be reversed so 30 as to tend to work the settled solids upwardly while passing through the pulp.

Outside the liquid or pulp in the settling vessel, the function of the rakes 24 is to keep the draining area of the inclined bottom 35 6 substantially free of solid material. In general, the angle of the rakes is such that out of the pulp and over the draining area they do not work the solid particles towards the periphery and into the path of 40 the annular system of scoops, but either push the solid particles along substantially in front of them and back to the pulp, rake the particles downwardly, or merely stir them as already described in some 45 50 detail.

The speed of rotation of the conveying element will be determined by the character of the classification desired. The faster the speed of rotation, the coarser the average 55 size of solid particles in the overflow product and conversely the slower the speed of rotation, the finer the average size of the solid particles in the overflow. As a result of the arrangement of the scoops or buckets 60 65 23, the improved classifier of the invention has a relatively large capacity as compared with other classifiers of the same general dimensions. The apparatus is susceptible of a relatively wide range in settling capacity, since the adjustable overflow makes possible

a relatively wide variation in the settling area of the basin. By appropriate adjustment of the speed of rotation of the conveying element and of the height of the overflow discharge, relatively wide variations in 70 the classifying operation of the apparatus may be effected.

The improved apparatus of the invention differs essentially from all other rotary classifiers with which I am familiar in that it 75 collects the coarse material in rotary scoops which rotate around the inner periphery of the settling vessel through the liquid therein and thence over a draining zone and collect the accumulated material as they pass 80 through the liquid from the outer part of the settling area and convey such material with one movement and a single handling over the outer periphery of a drainage zone that in its inner portion is kept free of solids 85 that would divert drainage into the path of succeeding draining material.

In the improved apparatus of the invention, the scoop-like members 23 pick up the solid material as fast as it reaches the bottom 90 of the settling vessel 5, and convey that material in a relatively narrow annular path to the solids (sands) discharge outlet 25. The scoop-like members are of such capacity that they engage and carry out of the pulp 95 all of the solid material settling into the path of the scoops through the pulp, and thereby the apparatus is given relatively high capacity with relatively low power required to operate it and wear of parts.

The portion of the inclined bottom 6 of the settling vessel 5 above the normal operating liquid level may be considered as divided into two sections, namely (1) the annular path over which the solids are moved 100 by the scoop-like members 23 and (2) the draining area or drainage zone below that path. The draining area is kept clear of any solid material leaking out of the scoop-like members by the rotating rakes 24, so 105 110 that the draining area is thus free to receive all of the moisture draining from the solid material carried along by the scoop-like members and to convey such moisture directly back to the pulp in the settling vessel. The two sections of the inclined bottom 6 above the pulp level have distinctly different functions, the outer section serving as a path over which solid material (sands) is conducted to the discharge, while the inner section serves to conduct the moisture, draining from the material passing over the outer section, directly back to the pulp.

The rotating conveying element of my improved classifier is of very rigid construction. The plane of the bottom of this element is in close proximity to and close alignment with the inclined bottom 6 of the settling vessel. Sufficient mechanical clearance is, of course, provided, between the bot- 115 120 125

tom of the rotating conveying element and the inclined bottom 6 to permit free rotation of the element, to allow opportunity for drainage of moisture from the scoop-like members, and to allow the sands to pass into the path of the scoops in the lower or settling portion of the vessel. The conveying element is preferably suspended from overhead bearings, and may be so mounted as to allow of adjustment of the amount of clearance between it and the bottom of the settling vessel. The power consumption is relatively low in comparison with the capacity of the apparatus. In an apparatus 15 eight feet in width, I have secured excellent results by spacing the rim 21 and ring 22 approximately one foot apart, and providing sixteen equally spaced scoop-like members 23. In this machine the pockets 20 or buckets so provided were approximately eight inches in depth or height. These dimensions are given merely as illustrative, and are of course susceptible of wide variations without departing from the spirit and 25 scope of the invention. The spider 20 may have any desired number of spokes and any desired number of rakes may be mounted upon the spokes.

I claim:—

30 1. An apparatus of the character described comprising a vessel having an inclined bottom surface of which a substantial area thereof is above the normal operating liquid level in the vessel and constitutes a draining area, said draining area of said inclined bottom surface having a solids discharge associated therewith, and a conveying element operatively mounted in proximity to said bottom surface and provided with a 35 plurality of scoop-like members having an inner wall formed to oppose downward flow of the solids during upward travel, forming pockets adapted to move through the pulp in said vessel and gather up and remove 40 therefrom a quantity of solid material and to carry such solid material along an annular path across said draining area to said solids discharge while permitting the drainage of liquid from such solid material as the same 45 is carried along said path, and said vessel having an overflow outlet for liquid by which the liquid portion of the pulp is discharged from the apparatus.

50 2. An apparatus of the character described comprising a vessel having an inclined bottom surface of which a substantial area thereof is above the normal operating liquid level in the vessel and constitutes a draining area, said draining area of said inclined bottom surface having a solids discharge associated therewith, and a conveying element operatively mounted in proximity to said bottom surface and provided with a 55 plurality of scoop-like members forming pockets adapted to move through the pulp in said vessel and gather up and remove therefrom a quantity of solid material and to carry such solid material without substantial loss thereof across said draining area to said solids discharge while permitting the drainage of liquid from such solid material as the same is carried along said path, and means 60 cooperating with said conveying element for maintaining said draining area substantially free of solid material whereby the liquor draining from the solid material carried along by said scoop-like member is per-

70 vessel and gather up and remove therefrom a quantity of solid material and to carry such solid material along an annular path across said draining area to said solids discharge while permitting the drainage of liquid from such solid material as the same is carried along said path, and means 75 cooperating with said conveying element for maintaining said draining area substantially free of solid material whereby the liquor draining from the solid material carried along by said scoop-like member is permitted to flow freely back into the pulp in said vessel.

3. An apparatus of the character described 80 comprising a vessel having a substantially flat inclined bottom surface of which a substantial area thereof is above the normal operating liquid level in the vessel and constitutes a draining area, said draining area of 85 said inclined bottom surface having a solids discharge associated therewith, and a rotary conveying element operatively mounted in proximity to said bottom surface and provided with a plurality of scoop-like members having an inner wall formed to oppose downward flow of the solids during upward travel, forming pockets adapted to move in a relatively narrow annular path near the periphery of said bottom surface and to 90 gather up and remove a quantity of solid material during its passage through the pulp in said vessel and to carry such solid material without substantial loss thereof across said draining area to said solids discharge while permitting the drainage of liquid from such solid material as the same is carried along said path, and said vessel having an overflow outlet for liquid by 95 which the liquid portion of the pulp is discharged from the apparatus.

4. An apparatus of the character described 100 comprising a vessel having an inclined bottom surface of which a substantial area thereof is above the normal operating liquid level in the vessel and constitutes a draining area, said draining area of said inclined bottom surface having a solids discharge associated therewith, a conveying element 105 operatively mounted in proximity to said bottom surface and provided with a plurality of scoop-like members forming pockets adapted to move through the pulp in said vessel and gather up and remove therefrom a quantity of solid material and to carry 110 such solid material without substantial loss thereof across said draining area to said solids discharge while permitting the drainage of liquid from such solid material as the same is carried along said path, and means 115 cooperating with said conveying element for maintaining said draining area substantially free of solid material whereby the liquor draining from the solid material carried along by said scoop-like member is per-

100

105

110

115

120

130

mitted to flow freely back into the pulp in said vessel.

5. An apparatus of the character described comprising a vessel having an inclined bottom surface of which a substantial area thereof is above the normal operating liquid level in the vessel and constitutes a draining area, said draining area of said inclined bottom surface having a solids discharge associated therewith, and a rotary conveying element operatively mounted in proximity to said bottom surface and provided with a plurality of scoop-like members having an inner wall formed to oppose downward flow of the solids during upward travel, forming pockets adapted to move in an annular path near the periphery of said bottom surface and to gather up and remove during its passage through the pulp in said vessel a quantity of solid material and to carry such solid material without substantial loss thereof along a relatively narrow path across said draining area to said solids said inclined bottom surface having a solids discharge associated therewith, a conveying element operatively mounted in proximity to said bottom surface and provided with a plurality of scoop-like members forming pockets adapted to move through the pulp in said vessel and gather up and remove therefrom a quantity of solid material and to carry such solid material without substantial loss thereof across said draining area to said solids discharge while permitting the drainage of liquid from such solid material as the same is carried along said path, and a plurality of rake members operatively positioned on said conveying element so as to move over said draining area and maintain said area substantially free of solid material whereby the liquor draining from the solid material carried along by said scoop-like members is permitted to flow freely back into the pulp in said vessel.

25 path across said draining area to said solids discharge while permitting the drainage of liquid from such solid material as the same is carried along said path, said solids discharge being so located that the solids carried along by said scoop travel over substantially the entire length of the scoop's path across said draining area before reaching the solids discharge, and said vessel having an overflow outlet for liquid by which the liquid portion of the pulp is discharged from the apparatus.

30

8. A machine of the character described comprising a vessel having an inclined bottom surface and an outlet in the upper part thereof, and a rotary conveying element moving over said surface and including a scoop forming a pocket arranged to engage material collecting on the surface at the lower end thereof and carry it to said outlet, and rakes adapted to agitate the material so as to permit it to move downwardly into the path of said scoop.

90

95

35 from the apparatus.

35 6. An apparatus of the character described comprising a vessel having an inclined bottom surface of which a substantial area thereof is above the normal operating liquid level in the vessel and constitutes a 40 draining area, said draining area of said inclined bottom surface having a solids discharge associated therewith, and a conveying element operatively mounted in proximity to said bottom surface and provided with a plurality of scoop-like members 45 forming pockets adapted to move through the pulp in said vessel and gather up and remove therefrom a quantity of solid material and to carry such solid material along an annular path across said draining area to 50 said solids discharge while permitting the drainage of liquid from such solid material as the same is carried along said path, said conveying element also being provided with a plurality of rake members operatively positioned to move over said draining area and maintain said area substantially free of 55 solid material whereby the liquor draining from the solid material carried along by 60 said scoop-like members is permitted to flow freely back into the pulp in said vessel.

9. A machine of the character described comprising a vessel having an inclined bottom surface and an outlet in the upper part thereof, a series of radial arms mounted for rotation about an axis at right angles to 100 said surface, scoops forming pockets on the arms adapted to engage material collecting on the surface at the lower end thereof and carry it to said outlet, and rakes on the arms adapted to agitate the material so as to 105 permit it to move downwardly into the path of the scoops.

10. An apparatus of the character described comprising a vessel having an inclined surface therein upon which solids accumulate in settling out of the pulp in 110 the vessel, a substantial area of said inclined surface being above the normal operating liquid level in the vessel and constituting a draining area, said draining area of said inclined surface having a solids discharge 115 associated therewith, and a conveying element operatively mounted in proximity to said inclined surface and provided with a plurality of scoop-like members having an 120 inner wall formed to oppose downward flow of the solids during upward travel, forming 125

7. An apparatus of the character described comprising a vessel having an inclined bottom surface of which a substantial area thereof is above the normal operating 65 pockets adapted to move through the pulp and gather up and remove therefrom a quantity of solid material and to carry such solid material along an annular path across said 120

draining area to said solids discharge while permitting the drainage of liquid from such solid material as the same is carried along said path, and said vessel having an overflow outlet for liquid by which the liquid portion of the pulp is discharged from the apparatus.

11. An apparatus of the character described comprising a vessel having a substantially flat inclined surface therein upon which solids accumulate in settling out of the pulp in the vessel, a substantial area of said inclined surface being above the normal operating liquid level in the vessel and constituting a draining area, said draining area of said inclined surface having a solids discharge associated therewith, and a rotary conveying element operatively mounted in proximity to said inclined surface and pro-

vided with a plurality of scoop-like members having an inner wall formed to oppose downward flow of the solids during upward travel, forming pockets adapted to move in a relatively narrow annular path over said inclined surface and to gather up and remove a quantity of solid material during its passage through the pulp and to carry such solid material without substantial loss thereof across said draining area to said solids discharge while permitting the drainage of liquid from such solid material as the same is carried along said path, and said vessel having an overflow outlet for liquid by which the liquid portion of the pulp is discharged from the apparatus. 35

In testimony whereof I affix my signature.

HARRISON STREETER COE.
